UNITED STATES PATENT OFFICE.

JOSEPH MAUROD CRUCET AND MAX HERMAN GOLDSMITH, OF NEW YORK, N. Y.

DETACHABLE COUPLING FOR ELECTRIC FIXTURES.

1,174,694.

Specification of Letters Patent.

Patented Mar. 7, 1916.

Application filed September 12, 1914. Serial No. 861,461.

To all whom it may concern:

Be it known that we, JOSEPH M. CRUCET, a citizen of the United States, and MAX H. GOLDSMITH, a subject of Austria, and both residents of the city of New York, borough of Manhattan, in the county and State of New York, have invented a new and Improved Detachable Coupling for Electric Fixtures, of which the following is a full, clear, and exact description.

This invention relates to improvements in electric fixtures and more particularly to electric light fixtures.

The primary object of the invention is to provide an improved detachable coupling and system of wiring for electric fixtures as specified or a device for attaching and detaching brass or other electric fixtures to all styles of portables, electroliers and hanging electric lighting fixtures, whether of wood, metal, china, glass, composition, fiber or any material used for such portables, electroliers or fixtures, whereby a fixture having any number of light sockets can be employed without the necessity of rewiring either the portable, electrolier or fixture.

With the above and other objects in view, the invention resides in the peculiar combination and arrangement of parts to be hereinafter more fully described, illustrated and claimed, it being also an object to provide a device which is simple in construction, durable and efficient.

Reference is to be had to the accompanying drawings forming a part of this specification, in which similar characters of reference indicate corresponding parts in all the views, and in which—

Figure 1 is a side elevation partly in section of a portable equipped in accordance with our invention and showing a fixture with two lamp sockets and incandescent bulbs; Fig. 2 is a side elevation of a fixture having four lighting sockets and a corresponding number of bulbs; Fig. 3 is a side elevation illustrating the application of the invention to a hanging electric lighting fixture; Fig. 4 is an enlarged sectional view illustrating the improved coupling employed for connecting the fixture to the portable or electrolier; Fig. 5 is a plan view of one section of the coupling; Fig. 6 is a similar view of the other section of the coupling; Fig. 7 is a fragmentary side elevation illustrating one means of joining the

section to the coupling; and Fig. 8 is a similar view illustrating another method of joining the coupling but with the parts in position prior to the connecting thereof. 60

In carrying the invention into practice, in Fig. 1 a portable electrolier or stand 10 is shown for table or floor use and having an enlarged base 11 for supporting it in an upright position. A tube or conduit 12 65 extends vertically through the portable and is designed to carry the electric wires 13 for conveying the current to the lamp bulbs. In lieu of forming the fixture and portable or stand as a single part, as heretofore, the 70 fixture 14 is made separate from the portable, it being understood that the fixture may be constructed in any preferred way and provided with a shade 15 if desired. These fixtures are provided with varying 75 numbers of lamp sockets 16 to suit the particular requirements, and for purposes of illustration a fixture is shown in Fig. 1 provided with two of such sockets and in Fig. 2 a fixture of similar construction is 80 shown provided with four sockets and pull cords or chains 17 for operating the switches of the sockets to control the extinguishing or lighting of the electric light bulbs 18 carried by the sockets. 85

Heretofore in order to change the number of sockets so as to provide a greater or less number of lamps for a particular fixture, it was necessary to practically reconstruct the fixture and rewire both it and 90 the stand which were constructed in one, but the present invention aims to obviate this by having the portables and fixtures separately wired so that the fixtures with the varying numbers of lights can be attached to any portable or electrolier. For 95 this purpose an improved detachable coupling is provided, the same comprising a section 19 in the form of a circular shell having an interiorly threaded portion 20 100 by which it is coupled to the tube or conduit 12 so as to contact, if desired, with the upper end of the portable, which is clearly shown in Fig. 4 of the drawings, and thus includes the tube and connecting portions 105 of the tube and coupling section 19. The fixture 14 may also be in the form of a shell and carries a tube or conduit 21 to which the other section 22 of the coupling is connected as by means of a threaded attaching portion 23, the latter being interiorly threaded for connection with the exteriorly 110

threaded end of the conduit so that the lower end of the fixture may also contact with the section 22 and inclose the coacting ends of said section and the tube.

5 The electric fixtures, such as the fixture 14, while usually of brass, may be of any suitable material and may be attached to all styles of portables and electroliers, whether wood, metal, china, glass, composition or any material used for portables or electroliers, and for this purpose the sections 19 and 22 are provided with enlarged flanged portions 24 and 25, respectively, the flanged portion 25 or the flanged portion 10 which is exteriorly located to snugly receive the other, providing a shoulder 26 for contact by the edge of the other flanged portion, whereby in addition to making the sections of the coupling of such diameter as to 15 form a firm connection to prevent lateral play, a positive supporting face or surface for the fixture is produced.

The sections 19 and 22 may be connected by providing one flange with bayonet slots 25 27 to receive pins or bolts 28 projecting outwardly from the other flange so that by passing the pins or bolts into the slots and rotating the fixture the pins will travel along the inclined edges of the slots so that 30 the parts will be drawn into binding engagement. In lieu of providing the bayonet slots 27 with the entrance openings 29 through which the pins 28 enter from the free edges of one flange, said slots may be 35 pressed outwardly as shown at 30 beyond the external face of the flange to permit the entrance of out-pressed projections or beads 31 carried by the other flange into the slots for similarly bringing the sections of the 40 coupling into binding engagement.

Mounted in each coupling section is an insulator 32 of fiber, porcelain, hard rubber or composition, it being understood that the coupling sections may be made of metal suitably insulated or porcelain if desired. The conductors or electric wires 13 are attached to terminals 33 of contacts 34 anchored to the insulator in the section 19 and the electric conductors or wires 35 of the fixtures 45 extend through the tube 21 and correspondingly through a central opening in the conductor, as in the case of the wires 13, and are connected to the terminals 36 of spring contacts 37 anchored to the insulator in the 50 section 22 and projecting slightly from the flange portion or edge thereof so that when the coupling sections are brought together and rotated the contacts will be brought into engagement to complete the circuit through 55 the lamps to permit the lighting thereof. The wires 35 are arranged in accordance with the number of lamps carried by the 60

fixture without modifying the construction of the contacts so that the fixtures provided with the various numbers of lamps are all 65 suitable for attachment to the portables or electroliers without any change or modification or necessitating the rewiring of the parts. The insulators are shown attached to the sections of the coupling by means of 70 screws 38 to permit their convenient removal and attachment and each insulator is provided with a central opening 39 through which the conductors or electric wires pass, as is clearly shown in Figs. 4 75 and 5 of the drawings.

In Fig. 3 of the drawings the application of the invention to a hanging electric lighting fixture 40 is illustrated in which the lower end of the latter is provided with a 80 coupling section 41 corresponding to the section 22, while the lighting fixture 42 attached thereto is provided with a coupling section 43 corresponding to the section 19, the parts being connected to operate in the 85 same manner as heretofore described. It is also understood that the coupling is adapted for application to various other electric lighting fixtures or electroliers well within the scope of the invention and will lessen 90 the cost and danger of breaking fixtures in packing and shipping, permit the manufacturer, jobber, dealer or consumer to change the number of lights of any portable equipped with the device to a fixture with 95 any number of lights he may require without rewiring the portable or fixture.

Having thus described our invention, what we claim as new and desire to secure 100 by Letters Patent is:—

A coupling of the class described comprising a pair of coupling sections each having an annular flange, the flanges being telescopically fitted and detachably fastened by a slot and pin bayonet connection, a plate 105 of insulation fastened in each section and of considerably less thickness than the axial dimension of the flange, whereby a chamber is formed between the plates of the two sections, spring contacts on the opposed faces 110 of the insulation plates and shaped to engage and disengage by the relative turning of the sections in connecting and disconnecting the latter, and conductors extending through each plate and fastened to the contacts thereon.

In testimony whereof we have signed our names to this specification in the presence of two subscribing witnesses.

JOSEPH MAUROD CRUCET.
MAX HERMAN GOLDSMITH.
